(57) **CLAIM**

The ornamental design for a transfer robot, as shown and described.

DESCRIPTION

1. Transfer robot
- 1.1 : Perspective
- 1.2 : Perspective
- 1.3 : Front
- 1.4 : Back
- 1.5 : Right
- 1.6 : Left
- 1.7 : Top
- 1.8 : Bottom

The essential characteristics of the design are featured in its shape.

1 Claim, 8 Drawing Sheets
